UNITED STATES PATENT OFFICE.

LEONARD AUNES, OF CAMBRIDGE, MASSACHUSETTS.

PILE-DRIVER.

No. 918,944.

Specification of Letters Patent.

Patented April 20, 1909.

Application filed February 4, 1908. Serial No. 414,272.

To all whom it may concern:

Be it known that I, LEONARD AUNES, a citizen of the United States of America, residing at Cambridge, in the county of Suffolk 5 and State of Massachusetts, have invented new and useful Improvements in Pile-Drivers, of which the following is a specification.

This invention relates to pile drivers, the 10 object of the invention being to provide a simple, economical and efficient machine of the character referred to which will be under the control of a single operator and which embodies a self-contained motor for operating all parts of the machine, thus doing away 15 with the use of steam and water and the leaky joints, stuffing boxes and pistons incident to the use thereof.

With the above and other objects in view, 20 the invention consists in the improved construction, combination and arrangement of parts hereinafter fully described, illustrated and claimed.

In the accompanying drawings, Figure 1 is 25 a side elevation of the pile driver embodying the present invention, indicating by dotted lines the angular adjustment of the hammer and the guide frame therefor. Fig. 2 is a sectional front elevation of the machine. 30 Fig. 3 is a sectional plan view thereof. Fig. 4 is an enlarged detail sectional view of the hammer showing the chain-engaging hook and a portion of the locking means therefor. Fig. 5 is a section through the hammer taken 35 at right angles to Fig. 4. Fig. 6 is a perspective view of an attachment designed for driving a pile farther than the normal limits of the hammer will ordinarily permit. Fig. 7 is a perspective view of the hammer tripping 40 mechanism showing the parts thereof segregated.

The pile driver contemplated in this invention, in its preferred embodiment, embodies a truck or carrying frame embodying 45 longitudinal rails 1 and cross bars 2 connecting the rails 1 at any desired number of points, whereby a rigid truck frame is formed, the same being mounted upon carrying wheels 3 which are journaled in forks 4 having a swiveled connection with the truck frame so that the wheels 3 may be turned at suitable angles to form chocks for preventing movement of the truck frame in any direction when set up at the point where the pile

driver is to be used. The rails 1 also constitute track rails for the supporting wheels 5 of a superimposed truck embodying the longitudinal beams 6 and cross bars 7, the last named superimposed truck frame having the entire pile driving mechanism mounted 60 thereon and being adapted to be shifted lengthwise of the carrying truck frame to properly position the hammer of the pile driver with relation to the pile to be driven. The upper truck frame is connected with the lower truck frame by stirrups 8 which prevent disengagement between the wheels 5 and the track rails 1 said stirrups being secured to the superimposed truck frame and extending downward and hooking beneath 70 the longitudinal track rails 1 as clearly shown in Figs. 1 and 2.

The hammer or driver 9 is mounted to travel in a suitable guide frame embodying parallel uprights 10 provided in their inner 75 faces with guideways or grooves 11, which receive guide ribs 12 on opposite sides of the hammer as best shown in Fig. 3. The guides 10 are connected at their top by a cap or yoke bar 13 while the lower ends of said 80 guides are pivoted as shown at 14 to the superimposed truck frame whereby the guide frame as a whole is adapted to be set vertically as shown in full lines in Fig. 1 or at an angle from the vertical as indicated by dotted lines in the same figure. The guide frame has connected therewith side braces 15 which are pivotally connected at their lower 85 ends to the superimposed truck frame as shown at 16 and the guide frame is further 90 supported by means of adjustable longitudinal braces 16 which at their upper ends are pivotally connected to the guide frame as shown at 17, the lower ends thereof being pivotally connected at 18 to shoes 19 which 95 rest on top of rails 20 secured to and extending lengthwise of the tops of the rails 6 of the superimposed truck or carriage. Each of said shoes 19 comprises one or more upstanding lugs 21 to which the lower end of the adjacent longitudinal brace 16 is pivotally 100 connected and also comprises a portion which extends along the top of the rail 20 and is secured thereto by a fastener 22 which may consist of a screw or bolt adapted to enter any one of a series of holes 23 in the rail 20, whereby the shoes 19 may be moved 105 along the rail 20 and secured to give the nec-

essary angle to the guide frame in which the hammer 9 moves.

The hammer is raised by means of an endless chain 24 which at the top runs over an 5 idler and take-up sprocket wheel 25, while at its lower portion said chain passes around a drive sprocket wheel 26 mounted fast on the main drive sprocket shaft 27 journaled in suitable bearings on the guide frame.

10 Motion is imparted to the shaft 27 and consequently to the hoisting chain 24 by means of a motor 28, preferably an electric motor mounted on the superimposed truck frame or carriage 6 as shown in Figs. 1 and 3, 15 the motor shaft 29 being provided with a pulley 30 from which a band 31 extends around and drives a larger pulley 32 and countershaft 33 journaled in suitable bearings on the frame. On the same shaft 33 is 20 another pulley 34 from which a drive band 35 extends around a pulley 36 on a pinion shaft 37 journaled on the machine frame and carrying a pinion 38 which meshes with a spur gear wheel 39 on a secondary shaft 40 25 mounted in bearings on the frame, said secondary shaft 40 having another spur gear wheel 41 which meshes with a similar wheel 42 preferably of larger diameter fast on the main sprocket shaft 27 above referred to. A 30 holding dog or pawl 43 on the frame engages the last named spur wheel 42 for locking the transmitting gears when the clutch herein-after described is thrown out. By the means just herein above described motion is transmitted 35 from the motor 28 to the hammer hoisting chain, adapting said chain to elevate the hammer as hereinafter described.

In order to effect an engagement and disengagement between the hammer and hoisting 40 chain therefor, the hammer has connected thereto a hook 44, the shank 45 of which works in a recess 46 in the hammer as shown in Figs. 4 and 5, and is pivotally mounted at its heel end within said recess as shown at 47, 45 the relation of the hook to the hammer being such that the hook has a normal tendency to fall into its operative position which is the position illustrated in Fig. 4 wherein the point of the hook projects beyond the point 50 of the hammer so as to be engaged by any of the cross-bars of the links of the hoisting chain. Journaled in bearings on the hammer 9 is a rock shaft 48 forming one element of the hammer tripping mechanism which 55 will now be described. The rock shaft 48 is provided with a laterally projecting stop lip 49 and opposite said stop lip is a lug 50 provided with a pivot receiving hole 51 for the pivot of a latch 52 having a corresponding 60 pivot hole 53 whereby the latch is pivotally connected to the rock shaft 48. The latch just under the pivot is provided with a weight 54 and a laterally projecting latch lip 55 which in one position of the pivoted latch

is adapted to engage a shoulder 56 preferably 65 in the form of a notch or slot in a cleat or projection 57 on the hammer 9. At its free end the latch 52 is provided with a slotted head 58 which embraces the rock shaft 48 and is adapted to move transversely of said 70 shaft as the latch as a whole swings on its pivotal connection with the rock shaft.

Just back of the pivoted latch 52 there is arranged a catch 59 which is given a normal tendency to spring into engagement with the 75 hook 44 by means of a spring 60 which is connected at one end by a lug or flange 61 to the hammer. It will be noted that the spring is U-shaped and that it is straddled by the catch 59, such shape of the spring permitting 80 the trip finger 62 of a trip lever 63 to move within the bend of the spring, adapting said finger to act thereon to throw the catch out of engagement with the hook. The trip lever is fulcrumed at 64 intermediate its ends 85 and in addition to the trip finger 62 said lever is provided with a trip cam 65 which co- 90 operates with the slotted head 58 of the pivoted latch in the manner hereinafter explained. The trip lever comprises a fork 66 between 95 the arms or branches of which operates a trip arm 67 projecting from a runner 68 which moves up and down on or lengthwise of a trip shaft 69. This trip shaft extends length- 100 wise of the hammer guide frame and is journaled at its opposite ends in suitable bearings thereon. The shaft 69 is preferably square in cross-section while the sleeve portion of the runner 68 is also square so that said runner is caused to turn with the shaft 69 and swing the trip arm 67 so that it will operate in the arm 66 to swing the trip lever 63 on its fulcrum.

By now referring to Fig. 3 in connection with Figs. 4, 5, and 7, and starting with the 105 hook 44 in its inward or withdrawn position, it will be observed that when the trip arm 67 is swung to the left in Fig. 3, it will move the trip finger 62 in the opposite direction and shift the catch 59 out of engagement with a 110 catch shoulder 70 at one side of the hook. This unlocks the hook which then swings forward by gravity to the position shown in Fig. 4 in readiness to be caught by the next link of the hoisting chain. As the hook 115 swings forward, the combined rock shaft and pivoted latch swing together so as to bring the stop lip 49 behind a stop shoulder 71 on the outer edge of the hook, the weight 54 assisting in this partial rotation of the shaft in 120 order to bring the stop lip 49 into a substantially pendent locking position. Simultaneously, with this locking movement of the shaft 48, the slotted head 58 drops and projects the latch lip 55 into engagement with the fixed shoulder 56, thus completely locking 125 the rock shaft against movement and thereby at the same time locking the hook 44

in its operative position, in which position the hook remains until the weight has been elevated to the desired point and it becomes necessary to release the weight or hammer. 5 The hook is released by turning the trip shaft 69 in the opposite direction which forces the trip cam 65 under the slotted head 58 of the latch 52. This raises the slotted head 58 and swings the latch and its pivot 10 and moves the latch lip 55 out of engagement with the shoulder 56. Then in the further movement of the trip cam 65 in the same direction, said cam acts on the slotted head to return the latter and as the latch 52 is connected to the rock shaft 40, the rock shaft is given a partial turn so as to rock the stop lip 49 upward out of engagement with the shoulder 71 of the hook. Now in view of the fact that the point of the hook 44 is considerably 15 to one side of the vertical line of its pivot 47, the upward pull of the hoisting chain on the hook 44 will cause said hook to be forced forward within the plane of the hammer and as the hook becomes disengaged from the hoisting chain, the hammer falls, striking the pile and driving the same in the usual manner. In view of the fact that the trip shaft 69 extends the entire height of the guide frame, and as the runner 68 moves lengthwise of said 20 shaft, being carried along by and with the hammer, the latter may be tripped at any point in the height of the guide frame.

In order that the runner 68 may be carried along with the hammer 9, the runner is provided as shown in Fig. 2 with a grooved collar 72 in the groove of which lie the arms of a carrier fork 73 which is connected to and carried by the hammer 9, the construction thus described causing the runner to travel with 25 the hammer while at the same time permitting said runner to turn with the shaft.

In order to impart the rotative movement to the trip shaft 69, said shaft is provided adjacent to its lower portion with a toothed segment 74 which meshes with one section 20 of a rack bar movable in a suitable guide on the machine frame, said rack bar comprising another section or series of teeth 76 engaged by a toothed segment 77 on a hand lever 78 movable over a supporting segment 79. This hand lever is placed where it will be in convenient reach of the operator who at any moment may swing said hand lever and correspondingly turn the trip shaft 69 for the 35 purpose above described.

In order to prevent the hammer from ascending too high and injuring or wrecking the machine, I provide in connection with the pinion 38, a sliding clutch 80 which is keyed to the clutch shaft and which has its clutch face 81 engaging a corresponding clutch face on the pinion 38 for locking said pinion to the pinion shaft. Associated with the clutch 80 is a clutch lever 82 fulcrumed

at 83 on the machine and having one end 65 yieldingly anchored by means of a spring 84 interposed between one end of said lever and a fixed point 85 on the machine, the last-named end of the frame being shown as connected to one extremity of the segment 79 70 for convenience. Connected to the opposite end of the clutch lever 82 is a cord 86 which extends around a guide pulley 87 upward to a sliding clutch trip 88 at or near the top of the guide frame, the said clutch trip being provided with a projecting finger or shoulder 89 with which the hammer comes in contact as it approaches the upper end of the guide frame. Then in the further upward movement of the hammer, the clutch trip is pushed 80 upward, drawing upward on the cord 86 and swinging the clutch lever so as to disengage or throw out the clutch 80. This throws the chain driving mechanism out of gear and the hammer stops before reaching the top of the 85 guide frame and remains there until it is tripped by the operator by means of the hand lever 78. As soon as the pressure of the hammer against the clutch trip 88 is relieved, the clutch lever is swung in the opposite direction by the spring 84 thus moving the clutch into engagement with the pinion 38 and again setting the driving gear in operation. 90

In order to adjust the tension of the hoisting chain 24, the upper sprocket wheel 25 has the shaft thereof journaled in bearings 90 which are adjustable up and down on the guide frame, said bearings being mounted in slots 91 and engaged by take up screws 92 100 threaded through bearings or nuts 93 on the frame, this adjustment being important and necessary in order to obviate backlash of the chain with the consequence to release the hammer. 105

In primarily setting the pile to be driven, the weight may be hoisted and held elevated by means of an auxiliary cable 94 which runs over a sheave 95 at the top of the guide frame and is provided with a hook 96 adapted to 110 engage a corresponding hook 97 on the top of the hammer, the cable 94 extending from the sheave 95 downward around a direction pulley 98 and then falling to an auxiliary pulley 99 shown as mounted on the countershaft 33 115 although it will be apparent that said pulley may be mounted on any other rotary shaft of the driving mechanism. This will enable the hammer to be elevated and suspended during the operation of setting a new pile. 120

When it becomes necessary to drive a pile farther than the lowest downward movement of the hammer as in the case of a submerged pile, I provide an attachment which is illustrated in detail in Fig. 6, said attachment 125 comprising a plunger or pile section 100 which is held adjacent to its upper end by a clamp collar 101 hinged as shown at 102 to a

plunger head or runner 103 having guide flanges 104 which move up and down in the guideways 11 of the guides. The runner 103 is set into the guide frame beneath the hammer, thus bringing the upper end of the plunger or pile section 100 directly in the path of the center of the hammer, while the lower end of said plunger is placed on the top of the pile to be driven, the hammer in its 10 downward stroke acting on the plunger instead of directly on the pile.

Having thus fully described the invention, what is claimed as new is:—

1. A pile driver comprising a frame, a 15 hammer, and a guide frame therefor, an endless hammer-hoisting chain, a hammer trip, and means including a shaft running lengthwise of the guide frame for throwing said trip at any point in the movement of the 20 hammer.

2. A pile driver comprising a frame, a hammer, a guide frame therefor, an endless hammer-hoisting chain, a hammer trip, and means including a shaft extending lengthwise of the guide frame and a runner thereon for throwing said trip at any point in the movement of the hammer.

3. A pile driver comprising a frame, a hammer, a guide frame therefor, an endless 30 hammer-hoisting chain, a hammer trip, and means including a shaft and runner movable on said shaft and carried along by the hammer for throwing said trip at any point in the movement of the hammer.

35 4. A pile driver comprising a frame, a hammer, a guide frame therefor, an endless hammer-hoisting chain, means for actuating said chain, and hammer-tripping mechanism including a movable chain engaging hook on 40 the hammer, a shoulder on said hammer, and a shiftable latch adapted to interlock with said shoulder.

45 5. A pile driver comprising a frame, a hammer, a guide frame therefor, an endless hammer-hoisting chain, means for actuating said chain, and hammer-tripping mechanism including a movable chain engaging hook on the hammer, a shoulder on said hammer, and a spring pressed latch adapted to snap into 50 engagement with said shoulder to lock the hook in its operative position.

55 6. A pile driver comprising a frame, a hammer, a guide frame therefor, an endless hammer-hoisting chain, means for actuating said chain, and hammer-tripping mechanism including a movable chain engaging hook on the hammer, a shoulder on said hammer, and a pivoted latch adapted to engage said shoulder for locking the hook in its operative 60 position.

65 7. A pile driver comprising a frame, a hammer, a guide frame therefor, an endless hammer-hoisting chain, means for actuating said chain, and hammer-tripping mechanism

including a movable chain engaging hook on 65 the hammer, a shoulder on said hammer, a rock shaft having a lip adapted to be engaged behind said shoulder and adapted to lock the hook in its operative position, and means for locking and rocking said shaft. 70

8. A pile driver comprising a frame, a hammer, a guide frame therefor, an endless hammer-hoisting chain, means for actuating said chain, and hammer-tripping mechanism including a movable chain engaging hook on 75 the hammer, a shoulder on said hammer, a rock shaft having a stop lip to engage said shoulder, a pivoted latch carried by the rock shaft and provided with a lip adapted to engage a fixed shoulder on the hammer to 80 rock the rock shaft, and means for releasing said latch.

9. A pile driver comprising a frame, a hammer, a guide frame therefor, an endless 85 hammer-hoisting chain, means for actuating said chain, a chain-engaging hook carried by the hammer, means on the hammer for locking and releasing said hammer, a shaft extending lengthwise of the guide frame, and a runner movable lengthwise of said shaft and 90 adapted upon rotation of the shaft to actuate the hammer-tripping mechanism carried by the hammer, substantially as described.

10. A pile driver comprising a frame, a hammer, a guide frame therefor, an endless 95 hammer-hoisting chain, means for actuating said chain, hammer-tripping mechanism carried by the hammer and including a trip lever, a trip shaft extending lengthwise of the guide frame, and a runner movable 100 lengthwise of said shaft simultaneously with the hammer and provided with a trip arm which is in engagement with the trip lever on the hammer.

11. A pile driver comprising a frame, a 105 hammer, a guide frame therefor, an endless hammer-hoisting chain, means for actuating said chain, hammer-tripping mechanism on the hammer including a trip lever, a trip shaft extending lengthwise of the guide 110 frame and embodying an arm which is in engagement with the trip lever on the hammer, and means within reach of the operator for rocking said trip shaft and tripping the hammer at any point between the limits of 115 its movement.

12. A pile driver comprising a frame, a hammer, a guide frame therefor, an endless hammer-hoisting chain, means for actuating said chain, tripping mechanism carried by 120 the hammer including a clutch lever, a trip shaft extending lengthwise of the guide frame, means for rocking said shaft, and a runner movable lengthwise of said shaft and yoked to the hammer, said runner being 125 keyed to the shaft to turn therewith.

13. A pile driver comprising a frame, a hammer, means for hoisting and tripping the

hammer, a plunger or pile section, and means for positioning and holding said plunger beneath the hammer and in the path of movement thereof.

14. A pile driver comprising a frame, a hammer, a guide frame, means for hoisting and tripping the hammer, a plunger or pile section adapted to be placed under the hammer and in the path thereof, and a plunger

head movable in the guide frame of the machine and having a jointed and adjustable connection with said plunger.

In testimony whereof I affix my signature in presence of two witnesses.

LEONARD AUNES.
